UNITED STATES PATENT OFFICE.

ALVAH C. ROEBUCK AND ADOLPH J. PRUSZYNSKI, OF WOODSTOCK, ILLINOIS, ASSIGNEES, BY DIRECT AND MESNE ASSIGNMENTS, TO WOODSTOCK TYPEWRITER COMPANY, OF WOODSTOCK, ILLINOIS, A CORPORATION OF ILLINOIS.

TYPE-WRITER BACK-SPACING MECHANISM.

1,214,715.

Specification of Letters Patent.

Patented Feb. 6, 1917.

Application filed October 26, 1914. Serial No. 368,562.

To all whom it may concern:

Be it known that we, ALVAH C. ROEBUCK and ADOLPH J. PRUSZYNSKI, citizens of the United States, residing at Woodstock, in the county of McHenry and State of Illinois, have invented certain new and useful Improvements in Type-Writer Back-Spacing Mechanism, of which the following is a specification.

10 This invention relates to mechanism for moving a typewriter carriage in a backward direction, and the principal object of the present invention is to provide improved mechanism of this class by means of which 15 the back spacing operation can be accomplished with what is known as a light touch.

For the attainment of these ends and the accomplishment of other new and useful objects, as will appear, the invention consists 20 in the features of novelty in the construction, combination and arrangement of the several parts generally shown in the accompanying drawing and described in the specification, but more particularly pointed out 25 in the appended claims.

In the drawings, Figure 1 is a side elevation of back spacing mechanism, constructed in accordance with the principles of our invention, standing in the normal or inoperative position; Fig. 2 is a detail view of the back spacing dog and operating lever; Fig. 3 is a view of the cam slot lever in operated position, and Fig. 4 is a detail view of the back spacing dog in engagement with the 35 rack bar.

In mechanism of this class, as previously employed, a considerable portion of the travel of the key lever was consumed in getting the back spacing dog or pawl into position to engage the rack on the carriage, while but a small portion of travel of the key lever was actually used to move the carriage backward one letter space. This resulted in requiring the application of considerable power to the key lever for operating the back spacer and moving the carriage backward one letter space, thus giving what is known as a heavy touch. In the present invention an improved construction and arrangement of operating levers is employed 50 by means of which the back spacing dog is moved quickly into position to engage the rack so that the greater part of the move-

ment of the key lever is used to move the carriage one space backward.

In the present invention the numeral 6 designates generally the frame of a typewriter machine in which a carriage 7 is transversely movable. Pivotedly mounted on the supports 8 in the carriage, is a rack bar 9 which is ordinarily in engagement with the escapement mechanism (not shown) but which may be disengaged therefrom by means of finger-hold 10 secured to the support 8, the rack bar being held yieldingly in such engagement by means of a spring 11. Mounted in the frame 6 below the rack bar is a throat plate 5 having an aperture 4, and pivoted on the frame is an operating lever 12 one arm of which is formed with spaced projections 13 and 14 and to which arm is pivoted a pawl 15 having a tooth 16 for engaging the teeth of the rack bar 9 through the aperture of the throat plate, a guard edge 17 adjacent and back of the tooth 16 for engaging the rear face of the rack to prevent it from being rotated rearwardly when the tooth 16 is in engagement with the rack, and with an arm 18 which engages the projections 13 and 14 for limiting the movement of the dog in both directions. A spring 19 is connected at one end to the dog 15 and at the other end to the operating lever 12 for holding the dog yieldingly in connection with the projection 14 when it is in operating position for engaging the rack bar 9.

When the lever 12 is at rest, as shown by Fig. 2, the arm 18 of the dog is held in contact with projection 13 by the engagement of the throat plate with the pawl caused by the right hand end of the lever 12, as shown by Fig. 2, being thrown downward by the action of mechanism connected thereto. As soon as the right hand end of the lever 12 is moved upward the pawl is moved out of engagement with the end of the aperture 4 of the throat plate, and the spring 19 moves the arm 18 of the dog in engagement with the projection 14. The tooth 16 of the dog engages one of the teeth of the rack 9, the guard edge 17 preventing the rotation of the rack 9, and the back spacing movement is continued until the dog 15 strikes the end of the aperture 4 in the throat plate which is usually of a length

to permit a back spacing movement of the rack one letter space. When the lever 12 is returned the parts again take the positions shown in full lines in Fig. 2.

5 Pivoted in the rear of the typewriter frame is a key lever 20 which has a key button 21 at the front of the machine and is provided with a guide 22 having a detent 23 for engaging a projection 24 and 10 limiting the downward movement of the lever. Intermediate the pivot point of the key lever and the forward end thereof, is a pivot 25 upon which is mounted a lever 26 formed with a cam slot 27 which has a substantially straight portion and a curved portion at its inner end. Secured to the key lever 20 is an anti-friction roller 28 for engaging the slot 27 and for moving the lever 26 first quickly on account of the 20 curved portion of the slot and then more slowly, but continuously, because of the straight portion. The lever 26 extends rearwardly to a point adjacent the rear extremity of the key lever and intermediate its 25 ends it is formed with a guide slot or surface 29. Projecting from the key lever 20 is a stud 30 having a flange which engages the opposite side of the lever 26, and by contact with the right hand side of the guide 30 slot 29 serves to hold the lever 26 in proper position with respect to the key lever 20.

A link 31 is pivotally connected at one end to the operating lever 12 and is provided with a stud 32 for engaging in a corresponding perforation in the rearward extension of the lever 26 with a spring clip 33 having a hook at the end for holding the lever 26 separably in connection therewith. The key lever 20 being pivoted at 40 the rear of the typewriter gives it a long leverage and the cam slot being near the pivot point of the lever 26 causes the other end of the lever 26 to be moved a considerable distance with a correspondingly small 45 movement of the key lever 20 during the initial part of its movement. The key lever is returned to its normal position by means of a spring 34.

In operation, the key lever 20 is depressed 50 by engagement with the key button 21 and the first part of the movement of the key lever causes the roller 28 to engage the curved part of the cam surface 27, whereupon the end of the lever 26, which is connected by means of the link 31 with the operating lever 12, is given a quick movement so that the tooth 16 of the dog 15 is moved out of contact with the throat plate 5 and into engagement with a tooth of the 55 rack bar 9, the dog being rotated by spring 19 so that the arm 18 is moved from engagement with the projection 13 until it contacts with the projection 14, whereupon the 60 guard edge 17 will prevent the movement 65 of the rack bar 9 about its axis, and the

continued movement of the key lever 20 will cause a continuous back spacing movement of the dog and the lever 12 by reason of the straight portion of the slot 27 in the lever 26. The key lever 20 having a long leverage requires only a quick light touch on the key button 21 to effect the back spacing movement. The movement of the key lever is limited by the stop 23, the movement of the dog is limited by the aperture of the throat plate, and after the back spacing movement of the carriage has been effected the spring 34 returns the key lever to normal position, the dog 15 being moved out of engagement by its contact with the end 70 of the throat plate aperture. 75

With this construction about one-third of the movement of the key lever is used to engage the pawl with the rack bar and the other two-thirds of the movement is used to move the rack bar and the carriage one letter space backward. Of course this proportion can be varied, as desired. 80

What we claim is:

1. In typewriter back spacing mechanism, the combination with a movable rack bar, of a back feed dog, a slotted plate to hold the dog normally out of engagement with the rack bar, the dog being movable through the plate into position to engage with the teeth of the rack, and mechanism to move the dog quickly through a small portion of its travel to engage the rack and to move the dog slowly in the back spacing direction through the remainder of its travel after 90 engagement with the rack. 95

2. In typewriter back spacing mechanism, the combination with a movable rack bar, of a back feed dog to engage the teeth of the rack and having a projecting arm, a pivoted lever to which the dog is pivoted having stops to engage the arm of the dog and limit its movement in both directions, a fixed slotted plate through which the dog extends, the dog normally engaging one end 100 of the slot to hold the dog out of engaging position with respect to the rack and in contact with one of the said projections, and means for moving the lever to actuate the 105 dog. 110

3. In typewriter back spacing mechanism, the combination with a movable rack bar, of a back feed dog to engage the teeth of the rack, a plate with a slot in which the dog moves and engages at one end to hold the dog out of rack engaging position, means for actuating the dog comprising a pivoted key lever, and means for limiting the movement of the key lever and the dog to one back space, said means comprising a detent 115 on the key lever and a fixed projection engaged thereby. 120

4. In typewriter back spacing mechanism, the combination with a movable rack bar, of a back feed dog provided with a guard 125 edge.

edge to engage the face of the rack and with a tooth to engage the teeth of the rack, and means for actuating the dog comprising a lever and an irregular slot engaged by the 5 lever for moving the tooth of the dog quickly into engagement with the teeth of the rack through a small portion of the travel of the lever and for continuing the movement of the dog at a slower speed in 10 the back spacing direction through the remainder and larger part of the travel of the lever.

5. In typewriter back spacing mechanism, the combination with a movable rack bar, 15 of a back feed dog for engaging and moving the rack in the back spacing direction, and means for actuating the dog comprising a pivoted lever with an irregular cam slot and a key lever with a member to engage in 20 a portion of the slot for moving the other lever with a quick initial movement and in another portion of the slot to produce a slower continuing movement in the same direction.

25 6. In typewriter back spacing mechanism, the combination with a movable rack bar, of a back feed dog adapted to engage and move the rack in the back spacing direction, and means for the dog comprising 30 a lever having a cam slot and a key lever having a roller in engagement with the slot whereby the continued movement of the key lever in one direction will cause the roller to engage and move the other lever quickly 35 during the initial portion of the movement of the key lever for moving the dog quickly into engagement with the rack and continuing the engagement with the cam slot for moving the dog and the rack in the back 40 spacing direction during the remainder of the movement of the key lever.

7. In typewriter back spacing mechanism, the combination with a movable rack bar, of a back spacing dog for engaging the 45 bar, means for actuating the dog comprising a lever formed with an operating cam slot and a guiding surface, a key lever, a contact roller in connection with the key lever for engaging the cam slot of the other lever, for engaging the cam slot of the other lever, 50 and a stud in connection with the key lever for engaging the said surface of the lever for guiding it in its operating movement.

8. In typewriting back spacing mechanism, the combination with a rack bar pivoted to swing about a longitudinal axis, and 55

movable longitudinally, a back feed dog provided with an arm, an operating lever for the dog comprising projections for limiting the movement of the dog in both directions, a spring attached at one end to the lever 60 and at the other end to the dog for moving it against one of the limiting projections, another lever formed with a cam slot and pivoted at right angles to the operating lever, a link connecting the two levers, and 65 a pivoted key lever with a roller for engaging the cam slot of the said other lever for communicating a quick initial movement to the operating lever whereby the dog is moved quickly in contact with the rack bar 70 and is then moved in the same direction to effect the back spacing movement of the rack bar.

9. In typewriter back spacing mechanism, the combination with a frame, of a key lever 75 pivoted adjacent the rear of the frame and extending to the front thereof, a lever pivoted intermediate the pivot point of the key lever and the front thereof and having an operating cam slot adjacent its pivot point, 80 means in connection with the key lever to engage the cam slot of the other lever for moving the latter at first with a quick movement and then with a slower movement, a movable rack bar, a back spacing dog for 85 engaging the rack bar, and means to connect the dog with the slotted lever for back spacing movement with the rack bar.

10. In typewriter back spacing mechanism, the combination with a movable rack 90 bar, of a back spacing dog for engaging the bar, means for actuating the dog comprising a lever having an operating cam slot and a guide surface, a key lever, a contact member in connection with the key lever for engaging the cam slot of the other lever, and a flanged stud in connection with the key 95 lever, the flange of which engages the opposite face of the lever adjacent the guide surface for holding the lever in position with respect to the key lever and for operating it.

In testimony whereof we have signed our names to this specification, in the presence of two subscribing witnesses, on this 22nd day of October A. D. 1914.
